UNITED STATES PATENT OFFICE.

RANDALL MCFARLAN, OF CINCINNATI, OHIO, ASSIGNEE TO THE WM. POWELL COMPANY, OF CINCINNATI, OHIO, A CORPORATION OF OHIO.

SELF-CLOSING VALVE.

Application filed November 21, 1924. Serial No. 751,333.

My invention relates to self closing valves particularly though not exclusively adapted for use on pipe lines requiring a rapid acting self closing valve.

5 The objects of my invention are to provide a simple, efficient, practical, economical and highly desirable throttle valve adapted to automatically close when the hand lever is released; to provide a self-closing throttle 10 valve adapted to effect considerable safety when used on gasoline supply pipe lines, in boiler rooms, gas plants, ice plants, soot-blowers, dyeing vats, turpentine tanks, canneries and can sterilizers or for keg washing 15 and barrel steaming or in other situations wherein it is adapted to effect its purpose.

My invention consists in providing a socket in the upper side of the disc carrier and adapted to receive a semi-ball having means 20 for supporting a compression spring which has its outer end supported by a detachable cap, so that when said disc carrier is manually operated into open position said spring is compressed and adapted to automatically 25 close the valve when the hand lever thereof is released.

My invention also consists in the combination, location and arrangement of parts and in the details of construction as herein 30 set forth and claimed:

In the drawings:

Fig. 1 is a side elevation of my invention showing the valve in a closed position and with the operating handle partly broken 35 away;

Fig. 2 is the same but showing the body portion partly broken away;

Fig. 3 is a side elevation of my invention showing the body portion partly broken 40 away and showing the valve in opened position;

Fig. 4 is a section taken on a line corresponding to 4—4 in Fig. 3;

Fig. 5 is a side elevation of the ball member or pivot plate;

Fig. 6 is a plan view of the same.

Fig. 7 is an end elevation of the disc carrier showing the pivot plate in operative position;

Fig. 8 is a side elevation of the same and showing the disc carrier partly broken away;

Fig. 9 is a plan view of the disc carrier; and

Fig. 10 is a perspective of the pivot plate.

In the preferred construction of my invention I provide usual valve body 1 having threaded inlet opening 2 and threaded outlet opening 3 for connecting suitable pipes. Within chamber 1' of the body is 60 disc carrier 4 having discs 5 and 6 disposed on either side thereof. Telescopic integral extensions 7 and 8, respectfully, of discs 5 and 6 are received through hole 9 in disc carrier 4 whereby discs 5 and 6, respectively, are maintained in adjustable wedged position against opposing seats 10 and 11 and whereby openings 2 and 3 are closed by manual operation of hand-lever 12 fixed to 65 projecting end 13 of shaft 14 journaled in boss 15 of the body and having end 16 of disc carrier 4 fixed to its inner end at 70 17.

To provide means for automatically actuating discs 5 and 6, respectively, in closed position upon seats 10 and 11 for closing 75 openings 2 and 3 in body 1 (as shown in Figs. 1 and 2), I provide socket 18, in top 19 of disc carrier 4 adapted to receive semi-ball 20 integral with circular plate 21 integral with upper portion 22 of the semi-ball for supporting the lower end 23 of coil spring 24 having its upper end 25 in engagement with inner end 26 of cap 27 threaded in orifice 28 in the upper portion of the body. Spring 24 is maintained on circular 80 plate 21 by centrally disposed boss 29 which is integral with the plate and extends into spring 24. Boss 29 has slightly less diameter than the inner diameter of spring 24, thereby permitting the lower end of the 85 spring to receive the boss.

In operation the mechanism of my invention is as follows:

Assume discs 5 and 6 are in closed position, as shown in Figs. 1 and 2.

Manual operation of hand lever 12 from the position shown in Figs. 1 and 2 to the position shown in Fig. 3 causes rotation of shaft 14 journaled in boss 15 of body 1, whereby disc carrier 4, having end 16 fixed 100 to inner end at 17 of shaft 14, is caused to move upwardly and carry with it discs 5 and 6 to the open position, as shown in Figs. 3 and 4, thereby compressing coil spring 24 as by ball 20 rotating in socket 105 18 in disc carrier 4 and carrying integral circular plate 21 upwardly.

Continuous manual pressure on hand lever 12, sufficient to overcome the compression in spring 24, maintains the valve in 110

opened position. When it is desired to close openings 2 and 3 of body 1, hand lever 12 is released, whereby coil spring 24 exerts sufficient pressure on plate 21 to cause disc 5 carrier 4 to move downwardly, permitting discs 5 and 6, respectively, to engage seats 10 and 11, thereby closing the openings.

An advantage of my invention is that when the valve is opened and hand or 10 manual pressure is released from hand lever 12, coil spring 24 automatically forces discs 5 and 6, respectively, into engagement with seats 10 and 11 adjacent openings 2 and 3, whereby the valve is closed. This construction is especially advantageous when the 15 valve is used for the purpose of permitting the flow of highly explosive liquids, such as gasoline for the reason that in the event the liquid accidentally becomes ignited, releasing hand pressure on hand lever 12 automatically closes the valve, thereby stopping the flow of liquid and greatly reducing the hazard of life and property caused by the conflagration. When used on pipe lines 20 containing acids, hot water or other dangerous liquids my invention considerably reduces the hazard to which the employees are subjected. Furthermore, the construction of my invention is extremely simple and 25 it is not likely to get out of order as the slight movement of semi-ball 20 in socket 18 is not sufficient to cause excessive wear and coil spring 24 is merely compressed and considerably within its elastic limit.

30 While I have shown and described my novel self-closing valve mechanism as adapted and intended for a particular type of valve it may also be used in any other situation to which it is adapted, and while 35 I have shown and described a particular construction of mechanism it will be understood that it may be varied in construction and arrangement, such as may be necessary for desired use in combination with valves having a varied construction of form, without departing from the scope or spirit thereof as defined in the claims.

40 What I claim as new and desire to secure by Letters Patent is:

50 1. A self closing valve comprising a body having an orifice and having an opening, a disc carrier having a socket therein, discs 55 slidably mounted on said carrier and adapted to close said opening, a pivot plate mounted in said socket, a coil spring, a cap in said orifice and having its inner end in engagement with said spring and a manually operative hand lever having connection with said carrier, whereby said discs are adapted to be removed from said opening and said spring is adapted to automatically force said discs in engagement with said body when said hand lever is released.

60 2. A self-closing valve comprising a body 65 having an orifice in its top and having an

inlet opening and an outlet opening oppositely disposed in the side thereof, a shaft journaled in said body, a disc carrier having one end fixed to said shaft and having a socket therein in the upper side of its free 70 end, a pair of discs loosely mounted on said carrier and adapted to close said openings, a pivot plate mounted in said socket and comprising a semi-ball, a pivotally mounted circular plate integral therewith and a boss 75 integral with said plate, a coil spring loosely mounted on said pivot plate and having said boss received in its lower end, a cap threaded in said orifice and having its upper inner end in engagement with the upper end 80 of said spring and a manually operative hand lever having connection with said carrier fixed to the projecting end of said shaft whereby said discs are adapted to be removed from said openings and said spring 85 is adapted to automatically force said discs in engagement with said body downwardly when said hand lever is released whereby said openings are closed.

3. A self-closing valve comprising a body 90 having an orifice and having an opening, a disc carrier having a socket therein, a disc mounted on said carrier and adapted to close said opening, a pivot plate mounted in said socket, a coil spring, a cap in said orifice and having its inner end in engagement with said spring and a manually operative hand lever having connection with said carrier whereby said disc is adapted to be removed from said opening and said spring 100 is adapted to automatically force said disc into sliding engagement with said body when said hand lever is released.

4. A self-closing valve comprising a body having an orifice in its top and having an 105 inlet opening and an outlet opening therein, a shaft journaled in said body, a disc carrier having one end fixed to said shaft and having a socket in the upper side of its free end, a pair of discs loosely mounted on said carrier and adapted to close said openings, respectively, a semi-ball pivotally mounted in said socket, a plate integral with said ball, a boss integral with said plate, a coil spring 110 loosely mounted on said plate and having said boss received in its lower end, a cap threaded into said orifice and having its upper inner end in engagement with the upper end of said spring and a manually 115 operative hand lever fixed to the projecting end of said shaft.

5. A self-closing valve comprising a body having an orifice in its top and having an inlet opening and an outlet opening therein, a shaft journaled in said body, a disc carrier fixed to said shaft and having a socket 125 therein, a pair of discs mounted on said disc carrier and adapted to close said openings, a semi-ball pivotally mounted in said socket, a plate integral with said ball, a boss inte- 130

gral with said plate, a coil spring loosely mounted on said plate and having said boss received in its lower end, a cap threaded into said orifice and having its upper inner end in engagement with the upper end of said spring and a manually operative hand lever fixed to said shaft whereby said spring is adapted to be compressed when said discs are removed from said openings.

- 10 6. A self-closing valve comprising a body having a threaded orifice in its top and having an inlet opening and an outlet opening therein, a shaft journaled in said body, a disc carrier having one end fixed to said shaft and having a socket therein, a pair of discs on said carrier and adapted to close said openings, respectively, a semi-ball mounted in said socket, a plate integral with said ball, a coil spring pivotally mounted 40 on said plate, a cap threaded into said orifice and having the upper end of said coil spring in engagement with the top of said cap and a manually operative hand lever fixed to said shaft and adapted to compress said 45 spring and simultaneously remove said discs from said opening, whereby said spring is adapted to force said discs into closing engagement with said body when said lever is released.
- 30 7. In a gate valve comprising a hollow body having a threaded orifice in its top and having an inlet opening and an outlet opening, respectively, having opposing valve 50 seats adjacent the inner sides thereof, a shaft journaled in said body, a disc carrier

having one end fixed to said shaft and having a socket in its free end, a pair of discs mounted on said carrier and adapted to engage said seats and close said openings, respectively, the combination of a semi-ball 45 pivotally mounted in said socket, a member integral with said ball, a coil spring loosely mounted on said member, means for retaining said lower end of said spring into engagement with said member, a cap threaded 50 to said orifice having its upper end in engagement with the upper end of said spring whereby said discs are adapted to be maintained in engagement with said seats.

8. A self-closing valve comprising a body 55 having an orifice therein having an inlet opening and an outlet opening, said openings being oppositely disposed, a shaft journaled in said body, a disc carrier having one end fixed to said shaft and having a socket 60 therein, a pair of discs slidably mounted on said carrier and adapted to close said openings, a ball member pivotally mounted in said socket, a coil spring mounted in engagement with said ball member, a cap secured in said orifice and having its upper 65 inner end in engagement with said spring whereby said discs are maintained in closed position and a manually operative hand lever fixed to the projecting end of said shaft whereby said discs are adapted to be actuated for removing said discs from said openings.

RANDALL McFARLAN.
